Primary Examiner — Freda S Nunn(74) *Attorney, Agent, or Firm* — Wood, Herron & Evans, LLP(57) **CLAIM**

The ornamental design for a keyboard for a tablet computer, as shown and described.

DESCRIPTION

FIG. 1 is a top front perspective view of a keyboard for a tablet computer showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a right side view thereof when the present keyboard is combined with a tablet computer; and,

FIG. 9 is a right side view thereof when the present keyboard is kept with a tablet computer.

Broken lines shown in the drawings illustrate portions of a tablet computer, and form no part of the claimed design.

1 Claim, 5 Drawing Sheets(56)
